UNITED STATES PATENT OFFICE.

JOHN LINDSAY AND ROBERT LINDSAY, OF DUNEDIN, NEW ZEALAND.

REVERSIBLE AND COLLAPSIBLE TROLLEY-POLE FOR ELECTRIC VEHICLES.

No. 895,378.

Specification of Letters Patent.

Patented Aug. 4, 1908.

Application filed November 6, 1907. Serial No. 400,950.

To all whom it may concern:

Be it known that we, JOHN LINDSAY, carpenter, and ROBERT LINDSAY, engine-driver, both subjects of the King of Great Britain, and residents of the city of Dunedin, in the British Colony of New Zealand, (whose post-office address is Dunedin,) have invented certain new and useful Improvements in Reversible and Collapsible Trolley-Poles for Electric Vehicles, of which the following is a specification.

The object of this invention is to produce a trolley pole for conveying the electricity from an electric cable to a moving vehicle, so that it can be reversed without breaking contact with the cable and also one that can automatically collapse if the trolley wheel gets off the electric cable, instead of being dangerous as now. The said pole is capable of being reversed from more than one place in a car. For this purpose the pole is either formed of two lengths and sizes of tubes, one to slide within the other, and normally kept extended by a spring in tension, or else the pole is formed of two lengths pivoted and capable of being partly folded either way while reversing, but which are normally kept towards a straight line by a spiral spring in tension. In either case the reversing is done by pulling the pole longitudinally over to the other position by a cord without breaking electrical contact with the cable.

An attachment can be added which allows the upper length of the pole to collapse, should the trolley wheel leave the cable.

Referring to the accompanying drawing:— Figure 1 is part side elevation and part longitudinal section of a pole partly drawn over for reversing, showing it shortened sufficiently to pass under the cable. Fig. 2 is a detail showing the upper pole collapsed, and a dotted outline of same in working position. Fig. 3 is an enlarged detail, a cross section of the pole where the spiral tension spring is. Fig. 4 is a side elevation of the folding pole with the collapsing attachment. Fig. 5 is an end elevation of part of same. Fig. 6 is a detail of a suitable spiral spring adjustment.

A² is the usual pole socket. A is the lower length of the telescoped pole and B is the smaller upper length preferably of other than round section, these are normally kept extended by the tension spring C.

D is a plate for the reversing cords, preferably hinged at D¹ to allow a slight side movement as shown. For collapsible poles, B has

a flush joint at B¹. The enlarged sliding lower end of B, B³, is connected to a slotted link H ending in a sliding ring H¹ which may have a roller to lessen friction. The roller 60 normally is kept down under the segmental guard G when the joint B¹ is still well within the tube A, a pair of these guards being arranged in reverse relation on opposite sides of the pivot of the pole. 65

In reversing the weight of the cable prevents the rise of the joint, but if the trolley wheel leaves the cable and the pole becomes too upright H¹ leaves the opening of the guard G and the spring C lifts the pole so that 70 the joint leaves A as in Fig. 2 when the top part collapses. A chain or cord attached to H¹ and brought to any convenient point will reerect the pole.

A¹ is the lower length of the folding pole 75 and B² the upper length. This modification will collapse in much the same way if needed, by H¹ and H leaving G and releasing the spring C¹ if the trolley wheel leaves the cable. Fig. 6 sets forth an adjusting arrangement at either end of spring C¹ if desired. 80

D² is a lug for the cords F F¹ used for reversing. These may be one cord, the body passing through the car round suitable pulleys not shown the ends being F and F¹ as shown 85 in Figs. 1 and 4.

E are the trolley wheels of usual make and E¹ the usual electric power cable.

It is obvious that a very elastic pole may be formed by the combination of the poles herein set forth, the lower length would telescope over the lower part of the middle length, with the spring as in Figs. 1 and 2; the upper part of the middle length would pivot to the top length with the trolley 90 wheel and has the tension spring as in Figs. 4 and 5, and this pole in three lengths would be suitable for high speed work and would lessen any jar in passing "frogs."

We have tried various plans but the poles herein set forth are believed to be the most effective. In this invention any suitable materials or sizes may be used. 100

Having described our invention what we claim and desire to obtain a patent of the 105 United States of America, is—

1. A reversible trolley pole, comprising a base section, an upper section capable of a lengthening and shortening movement relatively to the base section and supporting a trolley engaging device, means acting independently of the trolley wire for limiting the 110

- lengthening of the sections while the pole is in operative position, and means normally operating to extend the sections relatively to one another and permitting a shortening of the pole under the pressure of the trolley while the position of the pole is being reversed, said limiting device being inoperative while the pole occupies an abnormal position.
- 10 2. A reversible trolley pole, comprising a base section, an upper section slideable longitudinally of the base section and carrying a trolley engaging device, a guard coöperating with the upper section for limiting its movement while the pole is in an inclined position, and a spring normally operating to extend the sections relatively to one another and yieldable to permit a shortening of the pole under the pressure of the trolley while the pole is in a vertical position, said guard being disconnected from the upper pole section while the pole occupies said vertical position.
- 15 3. A reversible trolley pole, comprising a base section, a collapsible upper section pivoted on an axis transverse to the length of the base section, a spring normally acting to extend the sections relatively to one another and yieldable to permit a reversing of the pole while the latter remains in engagement with the trolley wire, and a guard coöperating with said spring for retaining the latter in active condition while the pole is in operative inclined position and disengaging from the spring to release the latter while the pole occupies an intermediate or vertical position.
- 20 4. A reversible trolley pole, comprising a base section, an upper section guided for movement longitudinally of the base section,

a spring normally acting to extend the sections relatively to one another, and a pair of reversely arranged segmental guards arranged on opposite sides of the pole and coöperating with said spring to retain the latter in active condition while the pole occupies either of two operative positions, said guards being inoperative relatively to the spring while the pole occupies an intermediate or vertical position.

5. A reversible trolley pole, comprising a base section, and intermediate and upper sections pivotally connected to one another on a transverse axis and adapted to telescope within the base section, the latter serving to retain the intermediate and upper sections in alinement when said sections are in telescoped position, a spring coöperating with the intermediate section and normally acting to telescope the intermediate and upper sections within the base section, the upper section being capable of bending laterally about its transverse axis when the upper section is extended beyond the base section, and a guard operatively connected to the intermediate section to retain the latter and a portion of the upper section in telescoped relation with the base section and disengaging from said intermediate section when the pole assumes a substantially vertical position.

In testimony whereof we have hereunto set our hands in the presence of two subscribing witnesses.

JOHN LINDSAY.
